BOILER CLEANER

Frederick W. Linaker, St. Louis, Mo.

Application May 28, 1936, Serial No. 82,181

6 Claims. (Cl. 122—392)

My invention has relation to improvements in boiler cleaners, and it consists in the novel features of construction more fully set forth in the specification and pointed out in the claims.

The invention is directed more particularly to the operating mechanism for the valve and the cleaner tube, and it has for its principal object the provision of two separate mechanisms, one for actuating the valve and the other for actuating the blower tube. While the actuation of the valve and the actuation of the blower tube follow each other in definite sequence, they have, nevertheless, separate and distinct actions and are not associated in synchronism. For instance, after opening the valve the operator may maintain said valve in open position for any desired period before proceeding with the actuation of the blower tube; and the extent of the arc of rotation of the blower tube in no wise imposes a variation in the degree to which the valve is opened. It is a further object of the invention to provide mechanism that will compel a complete rotation throughout the blowing arc of the blower tube before the valve may be closed, and also insure a complete opening of the valve before the blower tube may be rotated. These objects are accomplished with a single prime actuating device.

My improved boiler cleaner comprises an operating head, blower tube, a valve casing, valve actuating mechanism and blower tube actuating mechanism. The operating head is carried by the outer end of the blower tube, while the valve casing is primarily supported by the steam pipe or riser, and the actuating mechanism is carried by the valve casing.

The manner in which these boiler cleaner components are associated, as well as the details of construction thereof, will be better apparent from a description of the invention in connection with the accompanying drawings, in which:

Figure 1 is a side elevational view of my improved boiler cleaner with parts thereof shown in section; Fig. 2 is a front elevational view with parts broken away; Fig. 3 is a top plan view with parts broken away; Fig. 4 is a vertical cross sectional view taken on the line 4—4 of Fig. 1; Fig. 5 is a horizontal cross sectional view taken on the line 5—5 of Fig. 1; Fig. 6 is a rear elevational view of the hub portion of the operating sheave; Fig. 7 is a vertical cross sectional view through the operating sheave and indicated by the line 7—7 of Fig. 2; Fig. 8 is a front elevational view of the supporting bracket for the actuating

mechanism of both valve and blower tube; Fig. 9 is a horizontal cross sectional detail taken on the line 9—9 of Fig. 8; Fig. 10 is a side elevational view of the valve actuating cam; Fig. 11 is a cross sectional detail taken on the line 11—11 of Fig. 10; Figs. 12 and 13 are side and top views, respectively, of the stop bar which limits the rotation of the blower tube; Fig. 14 is a side view of the stop bar actuating cam; Figs. 15 to 17, inclusive, are diagrammatic views of the valve actuating mechanism showing the corresponding positions of the parts at the beginning of the first phase of the operating cycle, at which time the steam supply valve has not yet been opened; Fig. 18 is a diagrammatic view showing the relative positions of the blower tube, driving gear, stop bar, and valve mechanism driving pin at the same time depicted in Figs. 15 to 17, inclusive.

Figs. 19 to 21, inclusive, are diagrammatic views corresponding with those shown in Figs. 15 to 17, inclusive, with the parts moved, however, to their respective positions at the end of the first phase of the operating cycle, by which time the steam supply valve has been opened; Fig. 22 is a diagrammatic view of the same parts shown in Fig. 18 with the valve cam driving pin moved to a position corresponding with its position in Figs. 20 and 21; Figs. 23 to 25, inclusive, are diagrammatic views corresponding with those shown in Figs. 19 to 21 with the parts shown in their respective positions at the beginning of the second phase of the cycle of operations, which is the rotation of the blower tube, the valve remaining open; Fig. 26 shows the position of the blower tube driving gear, stop bar and valve cam actuating pin in their respective positions at the same time that the parts shown in Figs. 23 to 25 occupy the positions shown therein; Fig. 27 is a diagrammatic view showing the position of the stop bar actuating cam at the same instant that the parts shown in Figs. 23 to 25 are in the positions shown therein; Fig. 28 is a diagrammatic view of the stop bar and actuating cam therefor in their respective positions shortly after the second phase of the cycle of operations has gone into effect; Fig. 29 shows the same parts shown in Fig. 26, said parts being in their respective positions, however, at the end of the second phase of the cycle of operations; Fig. 30 shows the stop bar and actuating cam therefor also at the end of the second phase of the cycle; Fig. 31 is a diagrammatic view of the blower tube driving gear, stop bar and valve

cam driving pin just before the end of the third phase of the cycle;

Fig. 32 shows the stop bar and valve cam driving pin with relation to the supporting bracket 5 at the same instant depicted in Fig. 31; Fig. 33 is a diagrammatic view showing the relative positions of the valve cam, driving pin and hub of the actuating sheave at the end of the third phase; Fig. 34 is a diagrammatic view of the same parts shown in Fig. 21 showing the positions of the stop bar and valve driving pin relative to the supporting bracket at the end of the third phase; Figs. 35 and 36 are diagrammatic views corresponding to Figs. 31 and 32 showing the respective parts, however, at the end of the third phase 15 of the cycle.

Referring to the drawings, 1 represents the outer end of a blower tube of any construction known in the art which is passed through the customary wall sleeve 2 fixed in a boiler wall 3. A suitable bracket 3' is bolted to the flange 2' of the wall sleeve 2, and has a vertically disposed stud a which carries a loose ring bearing 3''. The operating head comprises a pair of spaced disc members 4, 5 connected by a flanged rib 6, and a disc member 7, which is bolted to the disc member 5. The outer extremity 1' of the blower tube 1 is screw-threaded into a central boss 7' formed on the disc member 7, and a tube 8 is disposed in the head having support in the disc 4 and in the disc 5. The end of the tube 8 within the disc 5 has a conical flange 9 between which and a central opening 10 in disc 5 is a bearing element 11.

The bearing element 11 is tightly held in place by the disc 7; thus, the bearing element 11 is frictionally held between the disc 5 and the disc 7 so that it will rotate with these elements while the tube 8 will remain stationary. In order to make the joint between these movable and stationary parts steam-tight, suitable packing material 12 is packed in the space behind the bearing element 11 and held in place by means of a gland 13, fixed by means of suitable bolts between the disc 4 and the disc 5. The construction of the head is substantially the same as the construction of the corresponding head shown in my pending application, Serial No. 755,135, filed November 28, 1934, and need not be described in greater detail as no claims are made for the head per se in this application.

A valve casing 14 is arranged in close proximity to the disc 4, said casing comprising a flanged component 15 (to which is bolted a steam supply pipe or riser 16) and an upwardly extending component 17, between which components is formed a steam chamber 18. A tapped opening 19 extends through the wall of the component 17 and has the outer threaded extremity 8' of the tube 8 screw-threaded into it so as to communicate with the steam chamber 18. Within the component 15 of valve casing 14 there is a suitable valve seat 20 disposed below the steam chamber 18, and a cylindrical chamber 21 disposed 65 above the steam chamber 18. The valve comprises a valve disc 22 and a guide disc 23, the latter slideable back and forth in the chamber 21 to move the valve disc 22 to and from the valve seat 20.

The valve disc 22 and guide disc 23 are connected by a suitable neck 24 through which passes a valve stem 25 extending upwardly through the valve casing 14. A stuffing box 26 is fixed in the casing to prevent leakage of steam past the valve stem. A pilot valve 27 is formed on the inner

end of the valve stem 25, and the seat 28 therefor is formed in the valve disc 22. The general construction and operation of the valve just described is the same as that of the valve of my co-pending application above referred to and will not be described in greater detail. A bracket 29 is fixed on the upwardly extending component 17 of the valve casing 14 and securely held in place by cap screws 30, 30 and said bracket has two spaced supporting standards 31, 32 for 10 supporting both the valve actuating mechanism and the blower tube actuating mechanism.

Actuating mechanism

An actuating shaft 33 is mounted for rotation 15 in the bearings 34, 35 formed at the upper ends of the arms 31, 32, said shaft having a clutch member 36 keyed to it near its outer end, beyond which extends a reduced threaded extremity 37. A chain sheave wheel 38 is loosely mounted on 20 the shaft 33 just inside the clutch member 36, said wheel having an outwardly projecting clutch housing 39 within which the clutch member 36 operates, said housing having an inwardly extending boss 40 which serves as a clutch member 25 for cooperation with the clutch member 36. A chain C passes over sheave 38 and is allowed to hang down within reach of the boiler attendant. A cylindrical opening 41 is formed in the boss 40 of housing 39, said opening having a flattened 30 shoulder 42 formed at its inner end, or that part of the opening which passes through the web 38' of the sheave 38.

A spring actuated bolt 43 is disposed in the opening 41, the flattened nose 44 of the bolt 35 bearing against the flattened shoulder 42 of the opening. The bolt is formed with an open socket 45 in which is seated a coiled spring 46; the outer end of said spring bearing against a perforated cover plate 47 held against the housing 39 by nuts 48, 49. The nose 44 of the bolt 43 normally projects a short distance beyond the inner surface of the sheave web 38'; and a driving lug 50 is formed on the outer surface of said web 38' on substantially the same arc as the bolt 43, but 45 spaced radially a short distance therefrom. A valve actuating cam 51 is loosely mounted on shaft 33 between bearing 34 and the sheave wheel 38, said cam having an arcuate flange 52 projecting outwardly from one side of its hub 53, 50 and a socket member 54 extending diametrically opposite from the flange 52. A cam surface 55 is formed on the hub 53 and socket member 54 and merges into the outer surface 56 of a cam nose 57 projecting outwardly from the socket 55 member 54. A longitudinally disposed cylindrical socket 58 is formed in the socket member 54, communicating with which and formed in the end wall 59 of socket member 54 is a square opening 60. A pin 61, hereinafter referred to as 60 the valve cam driving pin, is disposed in the socket 58, said pin having a square extremity 62 traversing opening 60 in member 54 and a shoulder 63 near its opposite end, between which and the bottom of socket 58 is a coiled spring 64 operating to urge the pin 61 inwardly so as to retract its square extremity 62 and extend its opposite end 65 beyond the socket 58. Thus, either one end or the other of the pin 61 always projects from the socket 58.

The bracket arm 31 has an arcuate portion 66 projecting beyond the bearing 34 through an angle of approximately 90 degrees, and the outer face 67 of said arcuate portion projects slightly beyond side surface 31' of bracket 31. Substan- 70 75

tially on the vertical center line of bracket arm 31, and adjacent to the inner end of arcuate portion 66, is a rectangular opening 68 immediately adjacent to which is a recess 69, the purpose of which will be apparent in connection with the description of the operation of the invention. A perforated arm 70 extends laterally from the bracket arm 31 and a lug 71, having an opening 72, also extends outwardly from the lug 71, but 10 in a plain at right angles to that at which the arm 70 is disposed. The bracket arm 32 is also provided with a rectangular opening 73 somewhat larger than the opening 68 but substantially on the same vertical center line. The cam surface 15 55 of the cam 51 is immediately above the valve stem 25, and a valve operating lever 14 is interposed between said cam surface and said valve stem. The pivotal end 75 of the lever is connected to the perforated arm 70 by means of a bolt 76. The upper end of the valve stem 25 passes through the opening 72 of the guide lug 71 and is held in contact with the bottom surface 20 of lever 14 by means of a spring 77 coiled about the valve stem 25 between the stuffing box 26 and a nut 78 passed over the threads 79 formed 25 on the upper end of valve stem 25. Obviously the action of the cam 51 on the lever 14 is communicated to the valve stem 25 whereby the valve is either opened or closed, although this is no 30 new expedient, having been heretofore employed by me in boiler cleaner construction. However, the specific form of cam and the association of other parts therewith is new, as will be herein-after more specifically pointed out.

35 On the inner end of the actuating shaft 33 is fixed a driving pinion 80, which meshes with a driving gear 81, fixed in any desirable manner on to the disc 4 so that with a rotation of the gear 81 the discs 4, 5, together with their connecting rib 6, comprising the blower head, will be rotated. In order that the driving gear 81 may have limits imposed on the extent of its rotation, there is a stop lug 82 formed on said gear 81, said lug projecting toward the bracket arm 32 and having a beveled face 82' (Fig. 3) adapted to cooperate with a stop bar 83, the outer end 84 of which is also beveled for this purpose. The stop bar is slidably mounted in the rectangular openings 68 and 73 in bracket arms 31, 32, respectively, and has a notch 85 formed in its inner end to receive the inner end 65 of valve cam actuating pin at a certain point in the cycle of operations to be shortly described. Considering the surface in which the notch 85 is formed 55 as the side of the stop bar 83, there is a recess 86 formed in the top surface thereof, said recess having its inner surface 87 inclined so that it will cooperate with a cam member 88 having oppositely disposed surfaces 89, 89, either of which is adapted to enter the recess 86 and engage the inclined surface 87 to slide the stop bar 83 toward the driving gear 81.

Having now described all of the parts which make up the actuating mechanism of my improved boiler cleaner, I will proceed with the 65 description of the operation thereof.

Operation of invention

In the diagrammatic views 15 to 18, inclusive, 70 the valve and the blower actuating parts are shown in their idle positions and the blower tube is at rest at the beginning of its arc of rotation. In order to actuate the blower, the operator takes hold of the chain C and pulls on 75 the same so as to rotate the sheave 38 in a counter

clockwise direction. As the sheave 38 rotates the lug 50, adjacent to the sheave hub, impinges on the pin 61, the end 62 of which projects in the path of said lug because the inner end 65 is bearing against the arcuate portion 66 of bracket arm 31. Thus, the rotation of the sheave 38 carries the pin 61 around with it and of course oscillates the cam member 51 which carries the pin 61. As the cam member rotates, its cam surface 55 forces the lever 14 downwardly and depresses the valve stem 25 so as to open first the pilot valve 27 and then the main valve 22, thereby admitting the steam from the riser 16 into the chamber 18 and, of course, to the blower tube 1. Throughout the oscillation of the cam member, the stop bar 83 occupies a position such that its outer end is clear of the pin 61, permitting said pin to travel over the end of the stop bar until it reaches the recess 69 in bracket arm 31, into which said pin drops and locks the cam member 51 against further movement. At this time the nose 57 of the cam member is bearing against the lever 14 to hold the valve stem 25 in its depressed position to maintain the valve 22 open. The valve actuating parts are now in the positions shown in the Figs. 19 to 22, inclusive.

The action just described may be termed the first phase of the operating cycle, during which only the valve has been actuated to open position, the blower tube remaining stationary. The second phase of the operating cycle, namely, the rotation of the blower tube throughout its blowing arc in one direction is accomplished by rotating the driving sheave 38 in a clockwise direction. Obviously the first part of the rotation of the sheave takes up the idle play between clutch members 36 and 40, after which the clutch member 40 in the sheave engages with the clutch member 36, carrying said clutch member around with it to rotate the actuating shaft 33 also in a clockwise direction (looking at the mechanism from the front). As the shaft 33 is rotated, the driving pinion 80 will also be rotated to actuate the driving gear 81, together with the blower tube with which it is connected in a counter clockwise direction. As the driving gear 81 rotates, the beveled stop lug 82 thereon moves away from the stop bar 83 without affecting the position thereof (Fig. 26). As the operator continues to rotate the sheave 38 by a clockwise direction, the pinion 80 rotates the gear 81 a complete revolution, during the beginning of which rotation one of the cams 89 on the cam member 88 has engaged with the inclined surface 87 of the stop member 83 to move said stop bar inwardly toward the gear 81. As the stop bar is moved inwardly by cam 89, its outer end releases the valve cam pin 61, permitting the force of main valve spring 77 to raise lever 14 slightly to oscillate the cam nose 57 and rock cam 51 until pin 61 comes over stop bar 83 (Fig. 29).

The movement of stop bar 83 inwardly puts the member in the path of the lug 82 so that at the end of one revolution of the gear 81, said lug 82 will come into abutting relation with the end of the stop member 83 as shown in Fig. 29. Figs. 27 and 28 show the action of the cam 88 on the stop bar 83. Obviously when the lug 82 engages with the stop bar 83, no further rotation of the gear 81 is possible and we have now come to the end of the second phase of the cycle of operations.

In order to complete the blowing operation of the boiler cleaner, the operator must now reverse the direction of rotation of the sheave 38. 75

He thereupon again rotates said sheave in a counter clockwise direction, during the first part of which rotation, while the play between the clutch members 36 and 40 is being taken up, 5 nothing happens to the valve mechanism. Continuation of the rotation of the sheave 38 in a counter clockwise direction now rotates the pinion 80 in a counter clockwise direction and the gear 81 in a clockwise direction until the outer 10 beveled face 82' of lug 82 impinges on the outer end 84 of the stop bar 83 to stop further movement. The engagement of face 82' with the beveled end 84 of stop bar 83 forces the bar outwardly carrying the cam actuating pin 61 clear 15 of the recess 69 and level with the arcuate surface 66. At this time the outer end of pin 61 is in the path of bolt 43, but said bolt will snap past the pin 61 (its spring yielding for this purpose) immediately before reaching the end of this phase 20 of the cycle. At this time we have come to the end of the third phase of the operating cycle and the blower tube has been restored to its initial position but the valve is still open (Figs. 33 to 36, inclusive).

25 We now come to the final phase of the cycle which is the closing of the main steam valve. Before commencing this final phase, the valve actuating parts are in their relative positions shown in Figs. 33, 34, and 36. The operator now 30 rotates the sheave 38 in a clockwise direction whereupon the bolt 43 (while the idle movement in the clutch is being taken up) carries with it in its rotation the cam pin 61 which is now held outwardly against the pressure of its spring 64 35 by the stop bar 83. The cam pin 61 thus travels over the arcuate surface 66 carrying with it the cam 51 and permitting the main valve to seat under the pressure of its spring 77. By the time arcuate lug 52 impinges against the bracket 31, 40 the valve is fully closed and the valve actuating parts are again in the position ready for beginning the first phase as shown in diagrammatic views 15 to 17, inclusive.

45 A complete cycle of operation has now been traversed and the parts have been restored to their positions of rest with the blower idle.

Having described my invention, I claim:

1. A boiler cleaner comprising a rotatable blower tube, an operating head including a revolvable support connected to the blower tube and a fixed support therefor, a valve casing in communication with the blower tube, a valve in said casing, actuating mechanism carried by the valve casing, said mechanism comprising valve-operating means and blower tube rotating means associated therewith and including a prime actuator sequentially effective on the blower tube throughout a predetermined arc forward and backward, means effective on the valve actuating 50 means to hold the valve open while the blower tube is rotating through its arc in both directions, and means associated with the blower tube actuating means to release said holding means during the rotation of the blower tube to provide for 55 closing the valve by the prime actuator after the end of the backward rotation of the blower tube.

2. A boiler cleaner comprising a rotatable blower tube, an operating head including a revolvable support connected to the blower tube and a fixed support therefor, a valve casing in communication with the blower tube, a valve in

said casing, actuating mechanism carried by the valve casing, said actuating mechanism comprising valve operating means, blower tube rotating means, and a prime actuator effective on both said means; the blower tube rotating means including driving elements connected between the blower tube and prime actuator by a clutch having a certain amount of free play, the valve operating means including a cam member, a retractile pin mounted therein, a driving lug on the prime actuator for engagement with said lug, a member for controlling the position of said pin whereby it may be held in and out of the path of the driving lug, a stop bar for limiting the amount of rotation of the blower tube, means associated with the blower tube for actuating the stop bar to move the retractile pin into the path of the driving lug, and separate means associated with the blower tube for actuating the stop bar to arrest rotation of the blower tube. 15

3. A boiler cleaner comprising a rotatable blower tube, an operating head including a revolvable support connected to the blower tube and a fixed support therefor, a valve casing in communication with the blower tube, a valve in said casing, actuating mechanism carried by the valve casing, said mechanism comprising valve-operating means and blower tube rotating means associated therewith and including a prime actuator sequentially effective on the valve and blower tube, means for locking the valve-operating means when the valve is open, a sliding bar operatively associated with the locking means, and a cam so associated with the blower tube and with the sliding bar as to move the sliding 30 bar into position to release said locking means. 35

4. A boiler cleaner comprising a rotatable blower tube, an operating head including a revolvable support connected to the blower tube and a fixed support therefor, a valve casing in communication with the blower tube, a valve in said casing, actuating mechanism carried by the valve casing, said actuating mechanism comprising valve operating means and blower rotating means associated therewith and including a prime actuator sequentially effective on the valve and on the blower tube, means for locking the valve operating means when the valve is open, a reciprocating member for unlocking said means, and means associated with the blower tube for actuating said reciprocating member. 45

5. A boiler cleaner having a rotatable blower tube, and a valve for admitting steam thereto, means for opening said valve, means for locking the valve in open position, means for rotating the blower tube effective thereon only after having locked the valve in open position, means for unlocking said valve effective after said rotation of the blower tube, and means for closing said valve. 55

6. In a boiler cleaner, a rotary cleaner tube, a valve for the admission of cleaning fluid thereto, a rotary operating head for said tube, means independent of said rotary head for opening and closing the valve, a common actuating means for operating said operating head and valve operating means in non-synchronized relation, the parts being constructed and arranged so that said valve operating means will operate to open the valve only prior to the rotation of the operating head and to close the valve only after the rotation of said operating head. 60

FREDERICK W. LINAKER.
